UNITED STATES PATENT OFFICE.

ROBERT HITCHEN, OF KEWANEE, ILLINOIS.

TUBULAR HOT-AIR FURNACE.

1,426,642.

Specification of Letters Patent. Patented Aug. 22, 1922.

Application filed January 31, 1922. Serial No. 523,074.

To all whom it may concern:

Be it known that I, ROBERT HITCHEN, a citizen of the United States, residing at Kewanee, in the county of Henry and State of Illinois, have invented certain new and useful Improvements in Tubular Hot-Air Furnaces, of which the following is a specification, reference being had therein to the accompanying drawings.

10 This invention relates to furnaces and more particularly to a tubular hot air furnace.

15 The object of the invention is the construction of an efficient and durable furnace, which will heat air and water at the same time, and with the heated air cause steam or vapor to be mixed, or mingle.

20 Another object is the construction of a furnace that is provided with means for heating water, at the same time air is heated for heating a building or dwelling, the heated water being utilized for many purposes, such as use in a bath-room, in a sink, or in a garage, and the like.

25 With these and other objects in view, my invention comprises certain novel combinations, constructions and arrangements of parts as will be hereinafter described, illustrated in the accompanying drawings, and 30 more particularly pointed out in the appended claims.

In the drawings:

Figure 1 is a vertical, sectional view of a furnace constructed in accordance with the 35 present invention.

Figure 2 is a sectional view, taken on line 2—2, Fig. 1, and looking in the direction of the arrows.

40 Figure 3 is a sectional view, taken on line 3—3, Fig. 1, and looking in the direction of the arrows.

Figure 4 is a sectional view, taken on line 4—4, Fig. 1, and looking in the direction of the arrows.

45 Referring to the drawings by numerals, 1 designates the furnace casing, in which is positioned the fire-box 2, around which is water jacket 3. The fire-box is provided with grate 4, and under the grate is the ash pit 5. Ashes are removed from the ash pit by means of door 6, whereas fuel is supplied to the fire-box by means of door 7 (dotted lines).

Cold air inlets 8—8 are formed upon the

casing 1 for allowing air to enter directly 55 from the cellar or basement in which the furnace is positioned, and air inlet 9 is provided for connection with piping that opens upon the outside of a building so that cold air from the outside may be allowed to pass 60 into the furnace.

The water jacket may be provided with outlet and inlet pipes 10—10 which may communicate with a bath, or a lavatory, or a sink, or a radiator; there may be as many 65 pipes 10 connected to the water jacket, as the operator desires. Tubes 11 are connected to a gravity tank (Figs. 1 and 3), not shown.

Metal tubes 12 are arranged in crossed position, Figs. 1 and 3, within the fire-box 2, 70 permitting fresh air to pass through the tubes and be greatly heated by the fire coming in direct contact with said tubes.

A humidifier receptacle 13 is fastened upon the outside of the fire-box 2, just under the 75 auxiliary casing 14. A vertical pipe 15 communicates at its lower end with the inside of water jacket 3, and its upper end discharges into receptacle 13; this pipe is provided with a manually-operated valve 16, whereby the 80 amount of water, passing through pipe 15 and discharged into receptacle 13, can be adjusted by the operator reaching through the outlet 9. The more water dropped or discharged into the receptacle, the more steam 85 will be generated and pass up with the heated air into the rooms of the building.

Extending through the auxiliary casing 14 is a hollow drum 15^a allowing the air to pass through the same and be heated, for the 90 flames from the fuel in fire-box 2 not only strike against tubes 12 but will also come in contact with the hollow drum 15^a.

The top of the auxiliary casing 14 is provided with a tubular extension 17 opening 95 into smoke pipe 18; smoke pipe 18 extends through the casing 1, to a flue (not shown) in any suitable manner.

The casing 1 is provided with a hot air outlet 19. 100

A horizontal baffle plate 20 is connected to the casing 1 and the fire-box 2 under the auxiliary casing 15^a. Baffle plates 21 (dotted lines) are fastened within the casing 1, being partly held against the fire-box 2, as 105 shown in Figs. 2 and 3.

The baffle plates act as braces and fastening means to assist in holding the parts to-

gether, and also serve to cause the air to circulate around the fire box in the hot air chamber, within casing 1.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In an apparatus of the class described, the combination of a furnace casing provided with inlets and an outlet, a fire-box in said casing, a water jacket formed upon said fire-box, a humidifier receptacle secured to the side of the fire-box, a pipe fastened at its lower end to the water jacket and overhanging at its upper end said humidifier receptacle, said pipe provided with a valve

contiguous to one of the inlets of the furnace casing, a smoke pipe, and means connecting said smoke pipe to said fire-box.

2. In an apparatus of the class described, the combination of a furnace casing provided with inlets and an outlet, a fire-box in said casing, a water jacket formed upon said fire-box, an auxiliary casing on the upper end of said fire-box and overhanging the same, a humidifier receptacle on the side of the fire-box and under said auxiliary casing, a valved pipe positioned contiguous to one of said inlets of the furnace casing and connected at one end to the water jacket and discharging at its other end into said humidifier receptacle, a hollow drum in said auxiliary casing, a smoke pipe, and means connecting said smoke pipe to said auxiliary casing.

In testimony whereof I hereunto affix my signature.

ROBERT HITCHEN.
